COMBINED PACKAGING CARD AND HANGER FOR AN ARTICLE OF MERCHANDISE

Michael C. Wilson, Wheaton, Ill., assignor to Pretty Products, Inc., Coshocton, Ohio

Filed Jan. 15, 1974, Ser. No. 433,551

Term of patent 14 years

Int. Cl. D9—99

U.S. Cl. D9—191

FIG. 1

FIG. 3

FIG. 1 is a perspective view of a combined packaging card and hanger for an article of merchandise,

FIG. 2 is a rear elevational view; and

FIG. 3 is a side elevational view thereof.

I claim:

The ornamental design for a combined packaging card and hanger for an article of merchandise, substantially as shown.
